WALTER E. BANNING, OF SYRACUSE, NEW YORK.

DESIGN FOR A BRANDING OR MARKING TOOL.

Design No. 16,657, dated April 27, 1886.

WALTER E. BANNING.
In presence of—
ROBT. H. ABBOTT,
GEO. D. WALSH.

UNITED STATES PATENT OFFICE.

WALTER E. BANNING, OF SYRACUSE, NEW YORK.

DESIGN FOR A BRANDING OR MARKING TOOL.

SPECIFICATION forming part of Design No. 16,657, dated April 27, 1886.

Application filed March 12, 1886. Serial No. 195,034. Term of patent 3½ years.

To all whom it may concern:

Be it known that I, WALTER E. BANNING, a citizen of the United States, residing at Syracuse, in the county of Onondaga and State of New York, have invented and produced a new and original Design for a Branding or Marking Tool, of which the following is a specification, reference being had to the accompanying drawings, forming part thereof.

10 In the drawings, Figures 1 and 2 represent, respectively, my original design for a branding or marking tool.

15 My design relates particularly to a branding or marking tool; and it consists, essentially, of a letter or figure having an octagonal handle portion, A, said handle having a gradual outward flare which ends at a horizontal rectangular ledge, B, situated directly above

the marking or indenting portion of said cast-iron letter or figure, the marking or indenting part proper being provided with converging sides, as indicated by the letter C.

Having described my design, what I claim is—

The design for a branding or marking tool, 25 the same consisting of a tool having an octagonal handle portion, A, flaring outwardly until it ends at a horizontal rectangular ledge, B, the marking or indenting portion having converging sides C, substantially as shown. 30

In witness whereof I have hereunto set my hand this 10th day of March, 1886.

WALTER E. BANNING.

In presence of—

ROBT. H. ABBOTT,
GEO. D. WALSH.
